US0D1110217S

(12) **United States Design Patent** (10) **Patent No.:** **US D1,110,217 S**
(45) **Date of Patent:** **** Jan. 27, 2026**

(54) **STEERING WHEEL FOR AUTOMOBILE**

(71) Applicants: **Hyundai Motor Company**, Seoul (KR); **Kia Corporation**, Seoul (KR)

(72) Inventors: **Dong Seong Lee**, Gyeonggi-do (KR); **Ju Yeon Jang**, Gyeonggi-do (KR); **Il Hun Yoon**, Gyeonggi-do (KR); **Sang Yup Lee**, Gyeonggi-do (KR); **Jae Ho Oh**, Gyeonggi-do (KR); **Jang Hyeok Ahn**, Gyeonggi-do (KR)

(73) Assignees: **Hyundai Motor Company**, Seoul (KR); **Kia Corporation**, Seoul (KR)

(**) Term: **15 Years**

(21) Appl. No.: **29/950,566**

(22) Filed: **Jul. 3, 2024**

(30) **Foreign Application Priority Data**

Mar. 25, 2024 (KR) 30-2024-0011406

(57) **CLAIM**

The ornamental design for steering wheel for automobile as shown and described.

DESCRIPTION

FIG. 1 is a perspective view of the subject design as viewed from the front.

FIG. 2 is a front view of the subject design.

FIG. 3 is a rear view of the subject design.

FIG. 4 is a left side view of the subject design.

FIG. 5 is a right side view of the subject design.

FIG. 6 is a top view of the subject design; and,

FIG. 7 is a bottom view of the subject design.

1 Claim, 7 Drawing Sheets

FIG. 1

FIG. 2

FIG. 3

FIG. 4

FIG. 5

FIG. 6

FIG. 7
